UNITED STATES PATENT OFFICE.

HARRY SCOTT, OF TOLEDO, OHIO.

COMBINATION FURNITURE.

Application filed July 19, 1922. Serial No. 576,057.

To all whom it may concern:

Be it known that I, HARRY SCOTT, a citizen of the United States, residing at Toledo, in the county of Lucas, State of Ohio, have 5 invented certain new and useful Improvements in Combination Furniture; and I do hereby declare the following to be a full, clear, and exact description of the invention, such as will enable others skilled in 10 the art to which it appertains to make and use the same.

This invention relates to new and useful improvements in furniture, and particularly to combination or convertible furniture.

15 One object of the invention is to provide an article of furniture which includes a novelly constructed and arranged bed, and which bed is adapted to be concealed within the article that its presence will not be 20 known.

Another object is to provide a device of this character which has simple, cheap, and durable means for mounting the bed so that the same may be easily and quickly moved 25 into or out of operative position.

Other objects and advantages will be apparent from the following description when taken in connection with the accompanying drawing.

30 In the drawing:

Figure 1 is a front elevation of an article of furniture made in accordance with the invention, the bed being in folded position.

Figure 2 is a side elevation showing the 35 bed in lowered position.

Figure 3 is a top plan view of the device in the position of Figure 2.

Figure 4 is a vertical sectional view 40 through the rear portion of the device, with the bed in folded position.

Referring particularly to the accompanying drawings, there is shown an article of furniture in the form of a bureau, indicated by the numeral 10, having the closet 45 11 at one side, and the bed receiving space 12 at the rear. Disposed horizontally through the space 12, and extending transversely of the bureau, is a rod 13, the inner end of which is secured in the inner end wall 50 14, of the rear compartment or space 12, said

rod extending a short distance outwardly of the outer end of said space.

The bed comprises a frame 15, having the spring bottom 16. One of the longer side members of the frame, that indicated by the numeral 17, being considerably wider than the other longer side, for the purpose of covering the outer open end of the space or compartment 12, when the bed is disposed therewithin. The frame is provided with foldable legs 18, for supporting the bed at the proper distance above the floor. Extending transversely of the foot end of the bed frame is a bar 19, which has an opening longitudinally therethrough for the reception of the before-mentioned rod 13, and on which rod the bed frame is adapted for pivotal movement into and out of operative position. Extending outwardly from the outer face of the side member 17, immediately outward of the end of the bar 19, is a knob 20, which serves as a handle by means of which the bed is raised and lowered on the rod 13, as its pivot.

When the bed is in the position of Figures 2 and 3, it is ready for use, the bed extending transversely of the end of the bureau, and being supported on its legs 18.

When the bed is to be placed out of use, the knob 20 is grasped and the bed swung 80 upwardly into a vertical position, opposite the open end of the compartment 12, and the bed then pushed into said compartment. As the bed is pushed into the compartment, the rod 13 slides into the bar 19, and the side 17 covers the open end of the compartment, thus forming the end wall of the 85 bureau, and concealing the bed.

What is claimed is:

The combination with an article of furniture having a compartment in the rear thereof of dimensions commensurate with the height and width of the article, and one end opening through one side of the article, a rod secured within the compartment and extending horizontally therein and through the open end thereof, and a bed frame having a transverse member slidably receiving the rod whereby the bed frame is capable of pivotal movement into and 100

out of vertical position with respect to the open end of the compartment and the side of the article, and slideable movement into and out of the compartment, one side of the bed frame having a panel for closing the end of the compartment to conceal the bed when therewithin.

In testimony whereof, I affix my signature, in the presence of two witnesses.

HARRY SCOTT.

Witnesses:

D. S. BURTSFIELD,
JAMES HOWARD.
